United States Patent Office.

JOHN HUNTINGTON, OF CLEVELAND, OHIO.

Letters Patent No. 100,766, dated March 15, 1870.

CONDENSER AND LIME-EXTRACTING HEATER

The Schedule referred to in these Letters Patent and making part of the same.

To all whom it may concern:

Be it known that I, JOHN HUNTINGTON, of Cleveland, in the county of Cuyahoga, and State of Ohio, have invented certain new and useful Improvements in Condenser and Lime-Extracting Heaters; and I do hereby declare that the following is a full and complete description of the same, reference being had to the accompanying drawings making part of this specification, in which—

Figure 1 is a vertical transverse section.

Figure 2, a top view of the inside.

Like letters of reference refer to like parts in the different views.

This invention has for its object the condensing of the exhaust steam of a steam-engine, and at the same time heating the water supplied the boiler, and extracting therefrom the lime held in solution, thereby supplying the boiler with pure water-condensed steam, thus preventing the incrustations of the boiler.

In fig. 1 A represents a shell or cylindrical case, the size of which being more or less, as the capacity of the engine may require.

Within said case is a series of conical-shaped diaphragms or partitions, B C, arranged one above the other, in the order as shown in the drawing, in which it will be seen that the upper or first one of the series B is of less diameter than the diameter of the case, and which is supported therein by being attached to the sides of the case by lugs D, fig. 2, thereby leaving a space, E, between the edge of the diaphragm and the side of the case.

It will be observed that the convexed side of the diaphragm B is upward, and terminates in a close top or point, whereas the second diaphragm C is so arranged that the convexed side is downward, and instead of having a close pointed crown, it is truncated, thereby forming an opening, F, at the center.

This diaphragm, as will be seen, is attached directly to the sides of the case in a tight, close manner, there being no space between it and the case.

The arrangement of the third diaphragm is like that of the first, the point or apex being directly under the opening of the diaphragm next above, and so on through the whole series of diaphragms, be there more or less. Thus each alternate diaphragm is attached directly to the side of the case, and provided with a hole in the center, and each alternate one attached to the sides of the case by means of lugs, leaving a space between it and the case, the apex of which is closed, and immediately under the opening of the next diaphragm above, as shown in fig. 1.

G is an induction steam-pipe;

H, an induction water-pipe;

I, an exhaust; and

J, the supply-pipe leading to the boiler.

The practical operation of this apparatus is as follows, viz:

It is placed in such position to the engine that the exhaust-pipe discharges into it through the pipe G. The exhaust steam ascends therein by passing upward through the space E at the side of the case, thence through the central opening F, from there again through the side spaces around the diaphragm, and so on to the top, as indicated by the arrows.

The apparatus being also connected to the pump, the water flows therein through the pipe H, and descends through the same passage-ways through which the steam ascends.

By this arrangement of diaphragms and passage-ways, it will be obvious that the volume of water forced into the apparatus is diffused over a large surface of heated metal. The steam, as it first enters, falls directly upon the apex of the cone-like diaphragm, and is thereby broken and diffused over the cone, falling down from the edges thereof into the inverted diaphragm immediately below, down which it flows to the central opening, and again upon the apex of another diaphragm, as before, and so on until it reaches the bottom of the apparatus, from which it is conducted by a pipe to the boiler in a highly-heated condition.

It will be obvious that the water, in its descent over the diaphragms and through the passage-ways, is met by the direct action of the steam at the points E and F, the two currents impinging upon each other in equal diffusion and concentration, the steam rapidly heating the water to a high temperature, and in turn the water condensing the steam, so that no steam escapes from the apparatus to the outside. A certain amount of cold air only passes from the apparatus through the exhaust-pipe I.

The water in its descent is driven back against the under side of the diaphragm by the direct action of the steam at the points E and E', and by its being thus diffused and atomized, the lime which it may have in solution is deposited upon the entire surface of the apparatus, but most abundantly on the under side of the diaphragms, and especially at the points K and E', the center and edges where the steam impinges with the greater force, and therefore attacks the lime with the greatest energy.

This precipitation of the lime is most thorough and complete, so that the water is given to the boiler free from its presence, hence no incrustations can take place in the boiler.

The lime deposits are removed from the apparatus through hand holes, indicated by the dotted lines a, into which the hand is introduced and the scale scraped off and taken out.

This apparatus is well adapted to marine engines,

as it can make little or no difference in its operation whether it stands exactly in a vertical position or at an angle. The descent of the water and the ascent of the steam will go on the same, there being no lodgement of the water in the apparatus, in consequence of its being thrown from a perpendicular end; hence no obstruction to the ascent of the inducted steam.

The diaphragms are represented as of a conical shape, the best adapted for marine purposes, but which, however, may be varied more or less from such shape to that of a low crown, sufficient only to run the water from the center to the circumference, and from thence to the center.

I am aware that conical-shaped diaphragms, constructed with alternate central and peripheral openings, have been before used in various forms of condensers and purifiers, but in all such either the steam enters near the upper part of the condenser, or if entering below the diaphragms, is permitted in large part to flow upward through a central vertical tube, and discharged near the upper part of the apparatus, a small portion only flowing out from side apertures provided in the vertical tube, while the water flows down through the annular openings or space outside the tube.

In my apparatus the entire current of steam is compelled to pass upward by the same course by which the water descends, the opposite currents therefore encountering each other at every point of their progress, until the steam is entirely condensed.

Furthermore, the central opening of my apparatus being entirely unobstructed, the steam dashes toward it and enters it from every direction, and the disturbance produced by the commingling currents of steam and water necessarily becomes greater than if the opening were so obstructed by a vertical tube or otherwise, as that, at any given point in the periphery of the opening, the steam could strike the descending

sheet of water upon one side only, merely dashing it against such obstruction, rather than, as in my invention, against other steam-currents.

As the perfection of the operation depends upon the intimacy with which the water and steam are commingled, it will be obvious that the unobstructed central opening, by producing a more perfect atomization of the water, must to the same degree more perfectly purify the water and condense the steam.

I am also aware that condensers have been used in which the water passes alternately from side to side, and falls from the edges of rectangular plates, and in which the entire volume of exhaust steam enters below such plates, encountering the descending water at each turn of its descent; but such condensers are materially different from mine, inasmuch as the water is not assaulted at one point, as at the central opening of my alternate diaphragms, where the steam can be projected into it from all directions.

I do not therefore claim, broadly, the use of conical diaphragms, when inclined alternately toward and from the axial line of the condenser; neither do I claim broadly the arrangement of the diaphragms in such way as that while the water in its descent passes from one side to the other, the entire volume of steam must encounter it at each point of its fall; but

What I claim as my invention, and desire to secure by Letters Patent, is—

A condenser and lime-extractor, provided with conical diaphragms, constructed with alternate peripheral and unobstructed central openings, substantially as and for the purpose set forth.

JOHN HUNTINGTON.
